WILHELM O. P. SCHUTTE, OF BROOKLYN, NEW YORK

METHOD OF ENGRAVING METALLIC SURFACES FOR PRINTING

Application filed September 29, 1930. Serial No. 485,218.

This invention relates to a method of engraving metallic surfaces to be subsequently used for printing purposes, and, while not necessarily restricted thereto, is particularly 5 designed as a method for engraving textile printing rollers.

At the present time, various and sundry methods are followed in engraving metallic surfaces for printing purposes, the principal 10 process or method consisting in first coating the metallic surface with a suitable acid resisting substance, such as asphaltum or its equivalent, and then by the use of a planigraph or equivalent means removing the acid 15 resisting substance to form a design, after which an etching or biting of the exposed surface is accomplished by an acid or mordant. This, together with the other methods now 20 in vogue, entails a considerable expense resulting from the amount of time and labor involved. It has also been observed that the prints produced from the surfaces prepared under the present methods lack the same quality and detail as accomplished by the method 25 which is hereinafter set forth.

It is, therefore, the general object of the present invention to accomplish by an etching process, the engraving of metallic surfaces for printing purposes, by virtue of 30 which prints of superior quality are obtained, while at the same time the method is simplified and the cost of engraving the designs is materially reduced, as well as the 35 length of time required to accomplish the method.

More specifically, the invention resides in a method of engraving textile printing roller surfaces or the like by an etching process 40 which includes the steps of outlining the desired design directly on the periphery or the surface to be engraved and then applying an acid resist to the roller periphery to develop the design by using the outline as a guide.

The invention furthermore resides in a 45 method which embodies the step of spraying by an air brush or other means, an acid resist directly onto the surface or periphery to develop a shaded design, either freehand or by 50 the use of an outline guide directly applied to the surface or periphery.

The invention with more particularity lies in a method of engraving by an etching process, a surface to be employed for printing purposes which includes the steps of applying a stencil sheet in intimate contact with 55 the periphery of a roller or with any other surface, together with the application of an acid resisting substance to the periphery or surface through the openings in the stencil, in a manner essential to the development of 60 the desired design.

The invention furthermore resides in a method of the character set forth which includes the spraying of an acid resisting substance on the uncovered portions of a surface 65 to be used for printing purposes, to develop a base which will subsequently print a uniform or shaded tint after the acid bite has engraved the surface exposed.

The invention has for a further object, the 70 engraving of a surface for printing which includes the steps of alternately spraying an acid resisting substance on the surface and subjecting the surface to acid bites while removing the acid and drying the surface between each operation to develop the desired 75 design.

As a still further object, the method covers the conceptional idea of successively applying 80 a plurality of stencils, in which the second and succeeding stencils are employed to cover previously uncovered portions of the surface, together with the application of acid resisting substances through the openings of 85 the stencils to develop the design desired.

With the above recited and other objects in view, reference is had to the following specification and accompanying drawing, in which one example or embodiment of the invention 90 has been disclosed by way of illustration, while the appended claims define the actual scope of the invention.

In the drawing:

Figure 1 is a fragmentary face view of a 95 printing surface with a stencil applied thereto.

Figure 2 is a similar view of the surface with the stencil removed after an acid 100 resisting substance has been applied to the sur-

face through the stencil openings and subsequent to the removal of the stencil.

Figure 3 is a view similar to Figure 2 illustrating the acid resisting substance applied completely around the design and with acid resisting substance uniformly sprayed on the exposed surface which defines the design.

Figure 4 is a view similar to Figure 3, with a second stencil applied having portions covering the previously uncovered portions of the surface, and illustrating the manner in which the sprayed exposed portions are intensified in certain areas to develop a shaded effect.

Figure 5 is a view similar to Figure 4, with the second stencil removed, and illustrating a further intensification of one of the sprayed portions covered by the second stencil.

Figure 6 is a view of the engraved surface after the acid bite and after the removal of the acid resisting substance.

Figure 7 is an enlarged sectional view taken approximately on the line 7—7 of Figure 6.

In the method illustrated in the drawing, 25 A designates the surface of a metallic roller or other object to be engraved, and B a stencil, either of celluloid or any equivalent material, which is provided with the cut-out portions C defining a design element D which 30 is to be etched on the surface A. The stencil B is secured on the surface A so as to intimately contact therewith, any suitable means for securing the stencil in place being employed. After the stencil has been applied in its 35 intimate contact with the surface A, as illustrated in Figure 1, an acid resisting substance E, as illustrated in Figure 2, is applied through the openings C to the surface A and will appear as shown in Figure 2, 40 on the surface A when the stencil is removed. The remainder of the surface A may then be covered or filled in with the acid resisting substance to appear substantially as illustrated in Figure 3 of the drawing. The exposed surface defining the design D is then sprayed or stippled with an air brush or equivalent device, as indicated at F in Figure 3, to produce a substantially uniform coverage of the exposed design defining portion of the surface A.

If desired, a second stencil G having cut-out portions H differing from the cut-out portions C of the initial design may be employed to cover up portions I of the surface A which 55 were not covered by the original stencil B. The operator may then develop further intensified stippled portions J, as shown in Figure 4, with the acid resisting substance sprayed as indicated. At this point, it may 60 be mentioned, however, that the use of the second stencil may be dispensed with where it is not desired and the intensified stippling may be accomplished without the use of the 65 second stencil. It is also to be understood

that as many other stencils as desired may be used to develop the design in accordance with the desire of the operator. It is also apparent that as illustrated in Figure 5, one or more of the portions I covered by the second stencil G may be later developed as at K by the intensified stippling. After the design defining portion D has been developed in the manner illustrated in Figure 5, the exposed portions of the surface A are subjected to an acid bite to etch or engrave the surface. The acid resisting substance is then removed from the surface A and the etched or engraved design portion D will appear substantially as illustrated in Figure 6 of the drawing, the intensified stippled portions being of a lesser depth than the remaining stippled portions, to give the shaded effect on the print which is made from the roller or surface A.

Figure 7 clearly illustrates this effect, in which the deeper portions L represent the lighter stippled portions, while the shallower portions M represent the heavier stippled portions. When the surface A is subsequently inked, it is obvious that the deeper portions L will print a deeper shade of the color, while the shallower portions M will print a lighter shade. While the method set forth illustrates intaglio engraving, it is clearly apparent that the stencil sheets may carry either a positive or negative design, in which instance the background may be depressed with respect to an elevated design, without departing from the spirit or scope of the invention.

It is also within the scope of the present invention to broadly employ the use of a sprayed acid resisting substance on the uncovered portions of a surface to be used for printing purposes, in order to develop such a surface which will print either a uniform or shaded base tint.

The invention broadly provides a method which among other steps includes those of outlining the desired design on the surface of a roller or its equivalent and directly applying, either by an air brush or otherwise, an acid resisting substance to the surface to develop the design by using the outline as a guide.

The invention further resides in a method of engraving, by etching a printing surface by subjecting the exposed portions of the surface to a preliminary acid bite, removing said acid and drying the roller and then subsequently repeating the operation on the remaining exposed portions until the desired design is developed.

From the foregoing, it will thus be seen that a method of engraving metallic printing rollers or other equivalent metallic printing surfaces has been devised, which not only reduces the time and labor involved in en-

graving the same but materially reduces the expense incident to the production of engraved printing surfaces. It is also apparent that under this method, a plurality of 5 rollers or surfaces may be engraved to obtain a subsequent accurate registry on the prints where multi-color work is involved.

ered portion to vary the intensity of the sprayed resist for obtaining a shaded effect by the variation in the subsequent acid bite.

Signed at New York in the county of New York and State of New York this 27th day 70 of September A. D. 1930.

WILHELM C. P. SCHUTTE.

What is claimed is:

1. A method of engraving by an etching 10 process, a metallic surface for printing purposes, including the step of spraying an acid resisting substance onto the surface to vary the intensity of the sprayed resist for varying the depth of the acid bite to develop a 15 shaded design.

75

2. A method of engraving by an etching process, a metallic surface for printing purposes, including the step of spraying acid resist on portions of the surface to develop a 20 uniformly shaded base tint.

80

3. A method of engraving by an etching process, a metallic surface for printing purposes, including the steps of covering portions of the surface and spraying an acid 25 resisting substance on the uncovered portions of the surface to develop a uniformly shaded base tint.

85

4. A method of engraving by an etching process, a metallic surface for printing purposes, including the steps of covering portions of the surface with an acid resist to define by the uncovered portions thereof, a design, uniformly spraying the uncovered portions with an acid resist, subjecting said 30 exposed portions to a preliminary acid bite, removing the acid, drying the surface and subsequently applying additional acid resist over a part of the exposed portions to intensify said part and then subjecting the exposed 35 portions to an additional acid bite to develop a shaded design.

90

5. A method of engraving by an etching process, a metallic surface for printing purposes, including the steps of applying a stencil 40 sheet in intimate contact with the surface, uniformly spraying an acid resist onto the surface through the openings in the stencil, removing the stencil and spraying acid resist to intensify portions covered by the sprayed 45 acid resist.

105

6. A method of engraving by an etching process, a metallic surface for printing purposes, including the steps of applying a stencil sheet in intimate contact with the surface, uniformly spraying an acid resist onto the surface through the openings in the stencil 50 and spraying acid resist to intensify portions covered by the sprayed acid resist.

110

7. A method of engraving by an etching 55 process, a metallic surface to be used for printing reproductions therefrom, said method including the steps of partially covering by an acid resist said surface to define by the remaining uncovered portion a design and 60 then spraying an acid resist onto said uncov-
